UNITED STATES PATENT OFFICE.

BERNIE C. KRIDLER AND JAMES C. BOYLE, OF FLINT, MICHIGAN.

METHOD OF CONSTRUCTING ROOFS.

Application filed February 20, 1923. Serial No. 620,163.

To all whom it may concern:

Be it known that we, BERNIE C. KRIDLER and JAMES C. BOYLE, citizens of the United States, and residents of Flint, county of Genesee, State of Michigan, have invented new and useful Improvements in Methods of Constructing Roofs, of which the following is a full, clear, and exact description.

10 Among the principal objects which the present invention has in view are: to prevent the lifting of the exposed ends of shingle sections; to facilitate the construction of roofs using as a covering therefor shingle sheets formed from a pliable material having relatively narrow shingle end extensions; to avoid forming leak passages in the roof structure; and to reduce the time needed to construct a roof covering.

20 Drawings.

Figure 1 is a vertical section of a fragment of a roof constructed in accordance with the present method of forming the same;

25 Figure 2 is a top plan view on reduced scale of a section of roof constructed in accordance with the present method;

Figure 3 is a detail view showing a fragment of a shingle sheet employed in forming the roof.

Description.

Referring to the drawings it will be seen a shingle sheet 8 has a number of shingle end extensions, said extensions being separated each from the adjoining extension in semblance of the usual wooden shingle. The shingles are laid as seen best in Figures 1 and 2 upon furring strips 9 and an eaves board 10, said furring strips and eaves board being secured structurally upon rafters. The shingle sheets 8 are held upon the furring strips 9 and eaves board 10 by clips 13, the spring-like extensions 14 of which pass below the said furring strips and eaves board to clamp the same and the shingle superposed thereon.

50 The upper section of each clip, extending between the bends indicated by the numerals 20 and 21, is elongated, the length depending upon the desire of the owner or designer. An upright section 11 is provided which may be overturned to enfold two thicknesses of shingles.

To assist in installing the clip in service the spring section 14 is bent at 15 to form an outwardly flared end 16. The clips are sent on to the job shaped as shown at the lower left-hand end of Figure 1 of the drawings, the section 11 being disposed in perpendicular relation to the elongated body of the clip.

When provided with shingle strips 8 the method of forming the roof is as follows: Upon the rafters is first placed the eaves board 10, which is nailed home. Upon the board 10 is placed a half shingle sheet 8^a, the upper edge whereof coincides with the upper edge of the eaves board 10. To hold the shingle strip 8^a in position the clips 13 are slipped over the said shingle strip and the eaves board 10. A furring strip, such as 9, is then laid on the slanting rafters to rest against the upper edge of the eaves board 10. A shingle sheet 8 is then mounted so that the upright section 11 of each of the clips 13 engaging the eaves board 10 rests in each of the spaces 17 of the shingle sheets, which spaces form the shingle ends 18 of the said sheet. In this position it will be found that the upper edge of the shingle sheet 8 is unsupported. The mechanic now draws the furring strip 9 upward until the upper edge of the furring strip coincides with the upper edge of the shingle sheet 8. The upper edge of the shingle sheet 8 thus forms a guide to register with the furring strip 9 when properly disposed. Through the shingle sheet 8 and the furring strip 9 there is now driven a roofing nail which secures the furring strip 9 upon the roof rafters.

95 A second course of clips is then placed in position to enfold the upper edge of the shingle sheet and the furring strip 9, the ends 11 being extended.

100 A second sheet 8 is now placed in position so that the upstanding extensions 11 of the two courses of clips engage the one sheet. The clips of the first course engage the extremities of the shingle ends 18, and the clips of the second course rest within the spaces 17. The upper edge of this shingle sheet forms now a gauge for setting the second or succeeding furring strip 9 in the manner above described.

110 During the progress of the work and before the mechanic gets beyond reach of the upstanding ends 11 against which rest the

extremities of the shingle ends 18, he overturns the ends 11 to the position shown in the drawings. The overturned ends 11 thus constitute a firm retainer for the shingle ends 18 to prevent them from being lifted by wind or from warping out of shape.

When the roof is completed it will be found that each shingle end 18 is held by one of the overturned extensions 11 of the 10 clips 13 substantially as indicated in Figure 2 of the drawings.

It will be understood that while we have herein described the securing of the furring strips 19 by using the shingle strips as a 15 gauge, the furring strips may be independently set and secured without the nail passing through the shingle sheet. The shingle sheet is firmly secured by the upper and lower clips 13 at all times.

20 We claim:

A method of forming roofing structures when using shingles sheets having shingle ends spaced apart, consisting in mounting a series of clips having upright sections 25 disposed in service at a lower level than the body of said clips; then setting a shingle

sheet having shingle ends spaced apart so that the said upright sections rest within said spaces and in engagement with said shingle sheet at the upper ends of said spaces; then setting a furring strip on the rafters of the standing structure so that the upper edge of said strip coincides with the upper edge of said shingle sheet; then securing the furring strip on the roof 35 rafters; then setting a second series of clips having upright extensions at the lower ends thereof, said second series of clips being disposed in staggered relation to the first series of clips and in position coinciding with the spaces between the shingle ends of a second shingle sheet; then setting said second shingle sheet so that the extremities of the shingle ends thereof rest in contact with the upright sections of the 40 first series of clips and the inner ends of the spaces holding the upright sections of the second series of clips; and then overturning the upright sections of the first series of clips.

BERNIE C. KRIDLER.
JAMES C. BOYLE.
